U.S. Appl. No. 63/075,608, filed Sep. 8, 2020, Albertyn.

Primary Examiner — Gino Colan

(74) *Attorney, Agent, or Firm* — Knobbe, Martens, Olson & Bear, LLP

(57) **CLAIM**

The ornamental design for a utility pole step, as shown and described.

DESCRIPTION

FIG. 1 is a perspective view showing a top surface of a utility pole step.

FIG. 2 is a perspective view showing a bottom surface of the utility pole step of FIG. 1.

FIG. 3 is a right side view of the utility pole step of FIG. 1.

FIG. 4 is a left side view of the utility pole step of FIG. 1.

FIG. 5 is a front view of the utility pole step of FIG. 1.

FIG. 6 is a rear view of the utility pole step of FIG. 1.

FIG. 7 is a top view of the utility pole step of FIG. 1; and,

FIG. 8 is a bottom view of the utility pole step of FIG. 1.

The broken lines in the figures are for the purpose of illustrating portions of the utility pole step which form no part of the claimed design.

1 Claim, 6 Drawing Sheets
